UNITED STATES PATENT OFFICE

WARREN A. MARRISON, OF EAST ORANGE, NEW JERSEY, ASSIGNOR TO WESTERN ELECTRIC COMPANY, INCORPORATED, OF NEW YORK, N. Y., A CORPORATION OF NEW YORK

OSCILLATION GENERATOR

Application filed August 5, 1924. Serial No. 730,165.

This invention relates to oscillation generators and more particularly to generators having means for maintaining substantially constant the frequency of oscillations.

It is known that piezo electric devices may be used to control the frequency of oscillations generated by space discharge tube oscillators. The crystals used for controlling high frequency oscillators are frequently cut from quartz and it is found that they will respond to a number of frequencies with varying degrees of activity. There is usually one natural frequency at which the crystal gives the greatest response and in general, oscillators, the circuits of which include piezo electric devices, produce oscillations of a single frequency determined solely by the natural frequency of the crystal.

It has been customary in the past to cut the piezo crystals used in oscillation generators from quartz so that the dimension in the direction of the axis of vibration of the crystal is small as compared to the other dimensions. It is found that crystals so cut have a number of frequencies in the same neighborhood to which they respond to a substantially equal degree. When crystals of this character are employed for controlling the frequency of oscillation generators it is practically impossible to predict at which one of these neighboring frequencies oscillations will take place. The efficiency and other factors of the oscillator circuit at different frequencies have a considerable influence in determining the frequency of oscillations. Because of this difficulty of accurately predicting the frequency of the oscillations produced by an oscillator using a piezo electric control element as heretofore proposed, their application has been limited, in spite of the fact that oscillators having such control elements possess the great advantage that they generate oscillations of substantially constant frequency.

An object of the present invention is to control within narrow limits, the frequency of oscillations generated by an oscillator of this type.

Another object is to control the generation of electrical oscillations at any one of a plurality of frequencies.

A specific object is to selectively control the frequency of generated oscillations in accordance with any one of the natural frequencies of a plurality of piezo electric devices.

A further object is to compensate for the capacity between electrodes of a space discharge tube, arranged to produce oscillations at desired frequencies, to prevent the production of oscillations of undesired frequencies.

An additional object is to control the feed-back of energy from the output circuit to the input circuit of a space discharge tube oscillator so that oscillations of desired frequency only will be generated.

A feature of the invention relates to an oscillator controlled by a piezo electric crystal whereby oscillations of a plurality of different frequencies may be generated.

Another feature relates to a space discharge tube oscillator employing a piezo electric device to compensate for inter-electrode capacity of the tube, whereby the generation of oscillations of undesired frequencies is prevented.

A still further feature relates to a piezo crystal controlled oscillator wherein the crystal used is designed to have dimensions such that its response to some particular frequencies is substantially greater than its response to other closely adjacent frequencies.

An additional feature relates to an oscillation generator having means for selecting any one of a plurality of natural frequencies of a piezo electric control element.

In its more general aspects, the invention comprises an oscillation generating system including an amplifying element arranged in a regenerative circuit and a frequency control element coupled thereto. The frequency control element may preferably consist of a plurality of component parts. At least one of the component parts of the control element is included in the feed-back portion of the regenerative system. This part preferably is arranged to have an electrical reactance that is substantially equivalent to the reactance inherent in certain other portions of the system whereby a balance is maintained at certain frequencies to prevent the establishment of

parasitic or undesired oscillations. The component part just mentioned is arranged to co-operate with an additional part of the frequency control element for determining at 5 which one of a plurality of possible frequencies the system will operate. Oscillations are generated in the system at desired frequencies by virtue of the fact that the reactance of the first mentioned component part of the frequency control element, which balances the reactance of other portions of the system, falls 10 approximately to zero at the desired frequency. This component element which, for example, may be a piezo electric device is 15 preferably sharply resonant so as to maintain the frequency of oscillations substantially constant within very narrow limits.

The invention, both as to its organization and method of operation as well as the further objects, features and advantages thereof, will be more clearly understood by reference to the following description read in connection with the accompanying drawings in which:

25 Fig. 1 illustrates a piezo crystal controlled oscillator.

Fig. 2 illustrates an oscillator similar to that of Fig. 1 having an amplifier coupled to its output circuit.

30 Fig. 3, illustrates an oscillator similar to that of Fig. 1 having an amplifier coupled thereto by means of a two-winding transformer.

35 Figs. 4 and 5 illustrate a section of a quartz crystal showing the manner of cutting a piezo electric crystal therefrom.

The oscillator illustrated in Fig. 1 comprises a space discharge tube of the three-electrode type having an input circuit 11, an output circuit 12, and a feed-back circuit 13. The input circuit is connected to the control electrode and cathode of the tube and includes a resonant circuit comprising an adjustable condenser 14, in parallel with the inductance 40 coil 15. A lead connecting the mid-point of coil 15 to the cathode of tube 10 includes a battery 16 that is provided to supply a suitable average polarizing potential to the tube control electrode.

45 50 One terminal of the inductance 15 is connected to the control electrode, the opposite terminal is connected to the feed-back circuit 13. The latter includes a coupling device illustrated as a piezo electric element 17.

55 Space current is supplied to the tube by means of a battery 18 in series with an impedance 19. Output leads 20 and 21 are arranged to be connected to a load device such for example as an amplifier, modulator or 60 wire line. Lead 20 includes a blocking condenser 22 to prevent the passage of direct current from battery 18 into the load circuit. The cathode of tube 10 is heated by a source of current illustrated as a battery 23 in series 65 with a resistance 24.

Condenser 25, shown in dotted lines, represents the inherent capacity between the control electrode and anode of tube 10 including the capacity of leads connected thereto.

The piezo electric device 17 comprises conductive plates 26 adjacent to opposite sides of a piezo electric crystal 27. The crystal 27 is preferably a parallelopiped cut from quartz along one of the axes of symmetry as indicated in Fig. 4. The plates 26 are placed adjacent to the sides A and B, Fig. 4, of the parallelopiped. It is a well known property of crystals so cut that, when subjected to physical stress in the direction of the dotted axis, plus and minus charges appear on the faces A and B and when subjected to an electrostatic field on the faces A and B it undergoes physical deformation along the dotted axis. The signs of the charges produced in the first case depend upon the character of the stress, that is, whether tension or compression, whereas in the second case the physical deformation, i. e., elongation or contraction under the action of an electrostatic field, depends upon the direction of the field.

If the stress changes from compression to tension or vice versa, the signs of the electric charges on the faces A and B are reversed, whereas if the electrostatic field is alternately reversed the crystal undergoes alternate elongation and contraction in the direction of the dotted axis, or in other words the crystal vibrates.

The crystal 27 is preferably cut as illustrated in Figs. 4 and 5 with its dimension in the direction of the axis of vibration, namely the dotted axis of Fig. 4, of the same order as its other dimensions. It is found that a crystal of such proportions has a plurality of natural frequencies but that its response to the fundamental frequency is substantially greater than its response to other frequencies which moreover are not in the same neighborhood.

An advantage of the present invention lies in the provision of means for selecting any one of the natural frequencies of the piezo electric device at which it is desired to generate oscillations and to prevent the production of oscillations corresponding to any other of its natural frequencies. This advantage constitutes a material improvement over any of the crystal controlled oscillators hitherto known.

The piezo electric device may be considered as a reactance which is high at frequencies other than those to which the crystal responds but is quite low or substantially zero at the resonant frequencies. This reactance property of the crystal may be utilized to explain the operation of the present invention.

The circuit of Fig. 1 operates to generate electrical oscillations by virtue of the feed back coupling supplied through the reactance of the piezo electric device 17. This is in the

nature of a capacity coupling. The frequency of oscillations is determined by the tuning of resonant circuit 14—15 and by the low reactance of the piezo electric device 17 at its 5 resonance frequencies. By adjusting the tuned circuit 14—15 to resonance at a particular frequency, the efficiency of the system for this frequency will be high by virtue of which oscillations of the selected frequency 10 will be produced. At frequencies other than those to which the crystal is responsive, the efficiency of the circuit is so reduced that oscillations of these frequencies can not be generated. Preferably the capacity of the 15 piezo electric device should normally be equal to that between the tube electrodes as indicated by the dotted condenser 25. For the frequencies at which the reactance of the piezo electric device 17 becomes very small 20 or zero, the circuit is sufficiently efficient to maintain oscillations provided the tuned circuit 14—15 is adjusted, as just explained, to resonance approximately at one of these frequencies.

25 To increase the number of frequencies that may be generated in this circuit, other crystals such as crystal 17' that are responsive to frequencies different from those to which the crystal 17 is responsive may be connected 30 in parallel thereto. Again by adjusting condenser 14 to the proper value the oscillator may be caused to produce oscillations at any desired one of the additional frequencies, and the crystal then acts to confine the frequency 35 of the oscillations produced, within very narrow limits to the selected value.

In one arrangement actually operated it was found that space discharge tubes having 40 different characteristics could be used in the circuit, and that the filament current and "B" battery potential could be changed without producing an appreciable effect upon the frequency of oscillations generated. Grounding and shielding of the circuit also produced a negligible frequency change.

50 In Fig. 2, the oscillator 28, which comprises space discharge tube 10, the resonant circuit 14—15 and the piezo electric device 17, may be identical with the oscillator of Fig. 1 although it is not illustrated as including the additional 17'. This oscillator is impedance coupled to a space discharge tube amplifier 29. The amplifier 29 has an input circuit connected to its control electrode and cathode, which includes resistance 30 in series 55 with battery 31. The space current circuit of the amplifier 29 includes impedance 32. The filaments of tubes 10 and 29 are heated in parallel by a source 23. A source 18 supplies space current to both of these tubes. Output leads 20 and 21 are arranged to supply energy from amplifier 29 to a load circuit. Blocking condenser 22 prevents current supplied by battery 18 from flowing in 60 the input circuit of amplifier 29. Condenser 65

22' serves to block the flow of direct current from battery 18 through a load circuit connected to leads 20 and 21.

In Fig. 3, a piezo electric crystal controlled oscillator 33 is coupled to a space discharge tube amplifier 34 by means of a two winding transformer 35. The oscillator illustrated in this figure corresponds to the oscillator in Figures 1 and 2 with the exception that the primary winding of transformer 70 35 replaces the resistance 19. The amplifier 34 comprises a space discharge tube 36 having a tuned circuit connected in its input circuit which includes the adjustable condenser 37 in parallel with the secondary winding 75 of transformer 35. The mid-point of this winding is connected to the filament of tube 36. One outer terminal is connected to the control electrode of this tube and the opposite terminal is connected to the anode of 80 tube 36 in series with compensating condenser 38. This condenser is arranged to balance the grid-plate capacity of the tube in order to prevent the production of parasitic oscillations in the amplifier circuit. 85 Space current is supplied to tube 36 by battery 18 through a series resistance 39. Output leads 20 and 21 are provided for connecting the amplifier to a load circuit which may be for example, another amplifier stage. 90 Blocking condenser 22'' serves the same purpose as condensers 22 and 22' as in Figures 1 and 2.

In the circuits of Figs. 2 and 3, oscillations are supplied from the crystal controlled oscillators to the respective amplifiers from which they may be supplied to any desired load circuit connected to the leads 20 and 21.

Obviously numerous modifications of the arrangements described above and involving 100 the principles of this invention could be made without departing from its spirit and scope. Accordingly, the present disclosure being merely representative of certain uses to which the invention may be applied, is 105 given for the purpose of completely and clearly explaining the principles involved. The invention therefore, is to be understood to be limited only by the scope of the appended claims.

110 What is claimed is:

1. An oscillation generator which comprises a three electrode space discharge tube, 115 input and output circuits for said tube, and means coupling said circuits to control the generation of oscillations comprising a piezo electric device, having its capacity proportioned with respect to the capacity between certain electrodes of said tube and being connected in the circuit to balance such inter-electrode capacity at all except desired oscillation frequencies, said piezo electric device serving as the principal frequency determining element at the desired oscillation frequencies.

2. An oscillation generator which comprises a space discharge device, input and output circuits for said device, said circuits being coupled to cause the generation of oscillations, and means comprising a piezo electric device for determining the degree of electrical coupling of said circuits to enable the generation of oscillations of a plurality of frequencies, said piezo electric device being proportioned with respect to the capacity between certain electrodes of said discharge device and being connected to balance the system against the production of oscillations at other than said plurality of oscillation frequencies.
3. In an oscillator a three electrode space discharge device, an input circuit connected to two electrodes of said device, an output circuit connected to one of said electrodes and a third electrode, said input and output circuits being coupled by inherent capacity between conductors thereof, and a piezo electric device having its capacity proportioned with respect to said inherent capacity, said piezo electric device being connected in circuit to balance the system against oscillations at all frequencies except those at which the piezo electric device oscillates.
4. In an oscillation generator, a three electrode space discharge device having input and output circuits, said circuits being coupled by the natural capacity of their conductors, and balancing means for said coupling capacity for controlling the generation of oscillations, said means having a capacity balancing the system against oscillations at some frequencies and substantially no reactance at other frequencies, whereby at the latter mentioned frequencies oscillations are produced under control of said means.
5. An oscillation generator which comprises a three electrode space discharge device, an input circuit connected to two electrodes of said device, said input circuit including a resonant circuit, an output circuit for said device, a piezo electric device electrically coupling said input and output circuits and cooperating with said resonant circuit to perfect a balanced bridged circuit except when the circuit as a whole oscillates at a resonant frequency of said device so as to determine the frequency of oscillations within narrow limits.
6. An electric oscillator comprising a three electrode space discharge tube, input and output circuits for said tube, said circuits being coupled together and means also electrically coupling said circuits to normally prevent the generation of oscillations in said oscillator, said means comprising a piezo electric device having substantially zero reactance at desired frequencies to allow the generation of oscillations of these frequencies and having at other frequencies a capacity balancing the inter-electrode capacity of said space discharge device whereby the tendency of the system to produce oscillations at other than said desired frequencies is effectively opposed.
7. An oscillation generator comprising an amplifying element having electrodes, a frequency control element comprising an electrically resonant element and a piezo electric device, said device being proportioned as to its capacity and connected in circuit to compensate for capacity between said electrodes to prevent the generation of undesired oscillations.
8. An oscillation generator comprising a space discharge tube amplifier having inherent capacity, a frequency control element coupled to said amplifier, said control element having substantial reactance at undesired frequencies and substantially zero reactance at desired frequencies, and so positioned as to cause its reactance to balance the capacity of said amplifier to thereby cause the generation of oscillations only at said desired frequencies.
9. An oscillation generator comprising an amplifying element including a three electrode space discharge tube, a frequency control element, having a plurality of component parts, one part of said control element being a piezo-electric device having substantial reactance at undesired frequencies and substantially zero reactance at a plurality of desired frequencies, said device having its capacity proportioned with respect to the capacity between electrodes of said tube and being connected to balance the system against oscillating at frequencies outside of certain definite ranges in the vicinity of the frequencies at which said device has substantially zero reactance, and means to select one of said plurality of desired frequencies at which oscillations shall be generated.
10. An oscillation generator which comprises, an amplifying element arranged in a regenerative system and having reactance tending to cause the production of oscillations, a frequency control element for determining the frequency at which oscillations may be generated, said control element including a piezo crystal having a dimension in the direction of the axis of vibration of the same order as its other dimensions and capacity reactance proportioned with respect to the reactance of said amplifying element and connected to balance said element against oscillating at selected frequencies.
11. An oscillation producing system comprising a space discharge device having a cathode, an anode and a grid or impedance controlling element, a piezo electric device, a resonant circuit comprising inductance and capacity having its terminals connected across said anode and grid elements except that said piezo electric device is included in series in the connection from said resonant

- circuit to one of said two elements, the cathode being connected to a point in said inductance intermediate its ends, whereby said system oscillates at frequencies at which said piezo electric device exhibits characteristically low reactance, the capacity of said piezo electric device opposing the regenerative effects of interelectrode capacity of said discharge device at other than said frequencies, whereby oscillations at said other frequencies are effectively prevented. 12. In a frequency control or stabilizing system a multiplicity of piezo electric crystals of different frequency characteristics and means for selectively sustaining the oscillations of any one of said crystals at its characteristic frequency. 13. In a frequency control or stabilizing system a multiplicity of piezo electric crystals of different frequency characteristics, an electron tube circuit common to all of said crystals, and means connected with said electron tube circuit for selectively sustaining the oscillations of any one of said crystals at its characteristic frequency. 14. In a frequency control or stabilizing system a multiplicity of piezo electric crystals of different frequency characteristics, an electron tube circuit connected with said crystals and an adjustably tuned circuit connected with said electron tube circuit for selectively sustaining the oscillations of any one of said crystals at its characteristic frequency. 15. The combination of a piezo electric crystal capable of vibrating at a plurality of frequencies, and means for sustaining the vibrations at one of the frequencies, said crystal being so positioned with relation to said means as to interpose a neutralizing reactive effect on said means for other frequencies than those at which the crystal is capable of vibrating, so as to oppose vibrations at such other frequencies. 16. An oscillation generator comprising a space discharge tube, an input circuit and an output circuit for said space discharge tube, said circuits being capacitatively coupled, a piezo electric device capable of vibrating at a plurality of frequencies, said piezo electric device controlling the frequency of the oscillations sustained by said coupled circuits, said device being so positioned with relation to said tube and its input and output circuits as to set up oscillations characteristic of a selected one of the frequencies of said piezo electric device, and to interpose a neutralizing reactive effect as to frequencies other than the frequencies of said piezo electric device, so as to prevent vibrations at such other frequencies. 17. In an electric wave transmission system comprising a piezo electric device having a vibrational crystal and electrodes, a method of selective transmission which comprises transmitting energy of a range of frequencies through said device and neutralizing the components of the energy transmitted by virtue of the inter-electrode capacitance of the device under static conditions. 18. In an electric wave transmission system, a piezo electric crystal resonator, a device having an inherent capacitance equal to the inter-electrode capacitance of said resonator under static conditions, and means to neutralize some of the components of the energy passed through the resonator by energy passed through the device. 19. In an electric wave transmission system, a plurality of piezo electric crystal resonators, a device having an inherent capacitance equal to the inter-electrode capacitances of all said resonators under static conditions, and means to neutralize some of the components of the energy passed through said resonators by energy passed through said device. 20. In an electric wave transmission system, a piezo electric crystal resonator, means to transmit energy through said resonator, and means to neutralize a component of said transmitted energy equal to the energy which would pass through said resonator if it did not resonate. 21. In an electric wave transmission system, a piezo electric crystal resonator, means to transmit energy through said resonator, and means to neutralize a component of said transmitted energy equal to the energy which would pass through a capacitance equal to the inter-electrode capacitance of said resonator when quiescent. In witness whereof, I hereunto subscribe my name this 29th day of July A. D., 1924.
